J. S. WHITTIER

SPARK PLUG

Filed June 15, 1923

Inventor
Joseph S. Whittier,

By *Eliza Bradford*

Attorney

UNITED STATES PATENT OFFICE.

JOSEPH S. WHITTIER, OF HOULTON, MAINE.

SPARK PLUG.

Application filed June 15, 1923. Serial No. 845,682.

To all whom it may concern:

Be it known that I, JOSEPH S. WHITTIER, a citizen of the United States, residing at Houlton, in the county of Aroostook and State of Maine, have invented certain new and useful improvements in Spark Plugs, of which the following is a specification.

My said invention relates to a spark plug and it is an object of the same to provide a device of the character described which shall produce a very hot spark, this result being obtained by creating a spark that is hollow and approximately of cylindrical shape.

Another object is to minimize the deposit of carbon on the sparking surface.

Referring to the accompanying drawings, which are made a part hereof and on which similar reference characters indicate similar parts,

20 Figure 1 is an elevation of my device with parts broken away to show the inner construction,

Figure 2, a bottom plan of the device with part of one terminal broken away, and

25 Figure 3, a detail of the terminals on an enlarged scale.

In the drawings reference character 10 indicates the body of a spark plug having the usual external thread 11 and having secured in place therein the usual porcelain body 12. A terminal 13 of ordinary construction is secured in the threaded skirt 11 and this terminal is preferably in the shape of a solid wire bent as shown and having a flat surface at the upper end of the bent part

30 14. A terminal 15 extends through the spark plug as usual, this terminal being bored out at its lower end to produce a cylindrical opening or cup at 16, which opening may of course be formed in any desirable manner and the shape of which may vary to some slight extent without departing from my invention. The conformation of this terminal causes the spark to assume a cylindrical or hollow form and to throw out an unusual amount of heat thereby more certainly insuring an ignition of the gases in the fuel chamber especially when the engine is cold or when the conditions are otherwise unfavorable.

At 17 I have indicated a fin or sharp edge formed by cutting an annular groove at 18 in the lower end of the terminal. The slot causes eddies in the gas as it rushes past the middle of the cup and this tends to prevent the deposit of carbon on the terminals. By this construction I secure a substantially hollow cylindrical spark which is hotter than the spark of the common plug and which is almost carbon-proof.

Having thus fully described my said invention, what I claim as new and desire to secure by Letters Patent, is:

1. A spark plug having opposed terminals one terminal having a hollow cylindrical conformation and being externally grooved to form a sharp annular fin adjacent to its lower end, substantially as set forth.

2. A spark plug having a rod-like terminal with a flat face, and an opposed hollow cylindrical terminal with a slot surrounding it near its lower end, substantially as set forth.

3. A spark plug having a rod-like terminal with a flat end surface, an opposed cylindrical terminal having a cylindrical pocket in its end and an external annular recess formed by an annular cut inclined to the axis of the terminal intersected by a cut substantially at right angles to the axis of said terminal, substantially as set forth.

4. A spark plug having a rod-like terminal with a flat end surface, an opposed cylindrical terminal having a cylindrical pocket in its end and an external annular recess formed by an annular cut extending inwardly from the circumference of the end of said terminal intersected by an annular cut substantially at right angles to the axis of said terminal, substantially as set forth.

In witness whereof, I have hereunto set my hand and seal at Houlton, Maine, this thirteenth day of June, A. D. nineteen hundred and twenty-three.

JOSEPH S. WHITTIER. [L. S.]

Witnesses:

L. J. HARRISON,
C. P. BARNES.
